ROTARY CAST CUTTER

Buford L. Cryar, Albertville, Ala.

Application March 23, 1945, Serial No. 584,310

3 Claims. (Cl. 30—167)

1

My present invention, in its broad aspect, has reference to improvements in rotary cutting implements for cutting casts from persons who have been injured and a part of the body placed in a cast. I have found that there are four primary objects to be attained, if a cast cutter is to be satisfactory, (1), the cutter and process of removal of the cast must cause a minimum of discomfort to the patient since the injured part is sensitive, (2), the chips and dust from the cast must be removed, (3), the implement must be light in weight and easily handled since otherwise, the process of cutting the cast will be clumsy and laborious and will be unduly tiring upon both the operator and patient, and (4), the construction must be simple, sturdy, practical and efficient with no small or intricate parts likely to get out of order or become broken or deranged. My present improvement accomplishes all of the above objects and purposes in addition to others which will be apparent from the following description and drawings, and it is pointed out that changes in form, size, shape, materials, and construction and arrangement of parts may be made and are within the purview of my broad inventive concept, and the scope of the appended claims.

In the drawings wherein I have illustrated a preferred form of my invention:

Figure 1 is a vertical section through the cutter;

Figure 2 is a side elevation of the rotary cutter;

Figure 3 is a top plan view; and

Figure 4 is a fragmentary view of the face of the cutter.

The numeral 1 designates a flexible shaft from a source of power (not shown) and which may be a small electric motor or the like. A side handle member 2 is bored to form a bearing for the cutter drive shaft 3 which is coupled as at 4 with the flexible shaft. A button switch 5 on the handle permits handy control of the motor (not shown). The handle has an enlarged end 6 which is annularly recessed as at 7 to receive the anti-frictional bearings 8 for the shaft which extends out from the end of the handle and has keyed thereto as at 9 a milled or grooved cutting wheel 10, on each side of which is a bearing collar 11, held in place by set screws 12. The end of the shaft beyond the outer bearing collar is journalled in another anti-friction bearing 13 supported in the cap 14 attached as at 15 to a semi-circular cutting wheel housing 15 having spaced parallel side walls connected by a web and which forms a guard hood over, and 55

2

protects and houses more than half of the cutting wheel and is attached as at 16 to the flange 17 on the handle end 6.

Mounted within the housing 15 is a brush 18 contacting the rotary cutter, there being a screw with a head 19 for attaching the same. Formed at the back of the housing 15 is a threaded sleeve 20 with which is engaged the threaded collar 21 of a hollow end handle 22 forming a conduit for dust, dirt and the like and having a connection 23 to a bag or the like (not shown) for receiving the chips, dust, dirt and the like. The back of the housing 15 is extended to each side of the sleeve 20 and below the end handle 22 to which is attached as at 24 the upstanding bifurcated shank 25 of a support 26 which has a curved face 27 directed about the back of the cutting wheel and spaced therefrom and a flat bottom 28 to which is attached as at 29 a forwardly projecting foot 30 having upper and lower inclined faces 31 and designed to follow in the cut formed in the cast (not shown) by the cutting wheel and to assist the cutting operation to the end that the cast will be comfortably, promptly and effectively removed.

From the foregoing, it is believed that the operation and advantages of my invention will be apparent, but it is again emphasized that interpretation of the scope of my invention should only be conclusive when made in the light of the subjoined claims.

I claim:

1. A rotary cast-cutter, comprising a rotary cutting blade, a housing for the blade, a shaft on which the blade is fixed, a side handle forming a bearing for the shaft, anti-friction bearings for the shaft, one carried by the handle and the other supported by the housing, a flexible drive shaft coupled with said shaft, a hollow end handle forming a conduit for dirt and chips and having an outlet connection, and a foot projecting beneath the cutting blade and supported from the housing.

2. The invention as defined in claim 1 wherein the housing is less than a full circle in elevation to expose a part of the blade, and a brush mounted in the housing and engaging the cutting blade.

3. The invention as defined in claim 1 wherein a support is mounted on the back of the housing and has a curved face following the curvature of the cutting wheel, and a bifurcated shank attached to the housing, and an elongated beveled foot attached to the support and projecting forward under and spaced from the cutting wheel.

BUFORD L. CRYAR.
